UNITED STATES PATENT OFFICE.

ARTHUR J. FILKINS, OF RIVERSIDE, ILLINOIS.

SMOKEJACK.

Application filed July 17, 1922. Serial No. 575,674.

To all whom it may concern:

Be it known that I, ARTHUR J. FILKINS, a citizen of the United States, residing at Riverside, in the county of Cook and State 5 of Illinois, have invented certain new and useful Improvements in Smokejacks, of which the following is a specification.

My invention relates to smokejacks which are provided in roundhouses and the like 10 for the purpose of withdrawing the exhaust gases and other combusted gases from locomotives and the like when within the roundhouse. My invention is particularly directed 15 to a form of smokejack which may be adapted to completely withdraw the exhaust gases from locomotives which locomotives may be stopped anywhere along the track in the engine stall within the roundhouse.

An object of my invention is to provide 20 a smokejack construction wherein all of the exhaust gases and the like may be carried away without permitting the escape of any gases within the roundhouse.

Another object of the invention is to provide 25 a smokejack having increased draft facilities for carrying away all exhaust gases from a locomotive irrespective of the position of the locomotive under the jack.

A further object of the invention is to 30 improve smokejacks for successful, commercial use.

Generally speaking, I carry out the preferred embodiment of my invention by providing a smokejack having an elongated 35 hood arranged over and along the track of the stall in the roundhouse whereby the exhaust gases from a locomotive may be received, and providing a plurality of ventilating outlets from the hood passing upwardly through the roof of the roundhouse.

Since the advent of large locomotives the use of the present type of smokejacks has been such as to make it impossible to withdraw all of the exhaust gases from the locomotive through the ventilating outlets of the jack. It has been the usual practice in roundhouse construction to place the jacks in such position that the locomotive would have to be stopped with its stack immediately under the hood of the jack. Carelessness in stopping locomotives has resulted in a partial removal of the exhaust gases with the result that a considerable portion of the gases is permitted to escape in the roundhouse, fouling the atmosphere therein. My invention overcomes the above recited

objection to the present form of smokejack.

The above recited and other objects of my invention will be apparent from the following description and drawings and will be particularly pointed out in the appended claims.

In the accompanying drawings:

Figure 1 is a side elevational view of the 65 preferred embodiment of my invention, and

Figure 2 is a partial end elevation of the arrangement of Figure 1.

In the form in which I have chosen to illustrate my invention I have shown a partial part of the roof 5 of a roundhouse. Suitably secured in the roof 5 is a plurality of depending bolts or stay rods 6. The smokejack of my invention comprises an elongated hood 7 which is made long enough 75 to extend some distance along a stall track and which has its ends 8 and 9 converging upwardly for the purpose of directing the exhaust gases from the locomotive towards the ventilating outlets. Referring to Fig. 80

Figure 2, it will be observed that the width of the hood is only slightly greater than the diameter of the ventilating outlets. The hood is made preferably with its sides of strips 10 of wood properly fireproofed and 85 with the end members 11 of castiron or the like, the parts being suitably secured together to form the hood of the invention.

At the upper portion of the hood designated at 12 I apply two diverging funnel-like 90

members 13 and 14 which are in arrangement and shape as shown in the drawing. These members are made preferably of metal such as castiron. Mounted on top of the members 13 and 14 are the ventilating 95 outlets A and B, each outlet being identical with the other as to manner of construction and arrangement. The outlets comprise a plurality of sections 15, cylindrical in form, the bottoms of which sections are provided with marginal flanges 16, having at diametrically opposite points apertured lugs 17 which register with apertured lugs 18 suitably secured to the next lower section. After bringing the adjacent sections together, bolts 100 19 are passed through the registering openings in the lugs 17 and 18 and secured by means of nuts applied to the ends thereof. This flanged construction provides a smoke-tight stack or outlet and one which may be 105 readily made, shipped and assembled in position.

The members 20, which top members 13 and 14 and communicate with the lower ends of lower section 15 of the outlets, are in shape and form made to correspond to the 5 section next below and next above, that is, rectangular below and circular above. The supporting stay rods 6 are secured by means of plates 21 fastened near the lower edges of the hood and which plates have laterally 10 extended apertured lugs 22 through which the lower ends of the stay rods 6 pass. Nuts 23 position the hood on the rods. As an additional means for supporting the smokejack in position from the roof 5 of the 15 roundhouse, other rods 24 depend from plates 25 and extend through apertured lugs 26 suitably secured to the members 13 and 14 of the jack. In like manner nuts 27 co-operate with the ends of the rods 24.

20 Where the ventilating outlets A and B pass through the roof 5 of the roundhouse, the roof is formed with enlarged openings 28 which are greater in diameter than the outside diameter of the outlets, and around 25 the upper marginal portions of the openings 28 are converging collar members 29 which support on their upper surface ring plates 25, having central openings 31 through which the ventilators A and B pass and 30 which although not specifically so shown are preferably greater in diameter than said ventilators, thus providing ventilating openings around pipes A and B. The sections 32 of the ventilators, which are the sections 35 passing through the roof, are not provided with the apertured lugs 18 as the case with the other sections. The bolts 33 passing through the apertured lugs 34 on the sections 35 of the ventilating members pass 40 downwardly through suitably disposed openings in the rings 25. As a means for preventing the admission of rain or the like through the ring plates 25 I mount a hood 30 adjacent the lower flange of the section 45 35 arranged to overlie the opening as shown. As a means for preventing the admission of rain or the like through the openings in the upper ends of the ventilating members A and B, and also to prevent excessive back 50 draft, I provide cover members 36 supported in spaced relation to the tops of the ventilating members A and B by bolts 37 passing through apertured lugs 38 suitably disposed near the upper end of sections 39 of the ventilating members.

55 A smokejack of my invention may be installed in a roundhouse with a hood over and along the track stall so that a locomotive may be stopped with its stack anywhere 60 underneath the hood whereupon the exhaust gases will be directed inwardly and upwardly through the ventilating members A and B. If for instance, the locomotive should be stopped near the left hand end of 65 the hood as viewed in Figure 1, most of the

gases would pass up through ventilator A. The gases which could not pass through this ventilator would be withdrawn through ventilator B. By reason of the open construction of the interior of the hood no 70 gases will escape under the edges of the hood and into the roundhouse. In like manner, if a locomotive be stopped with its stack near the right hand end of the hood, the greater portion of the gases would pass 75 through ventilator B, with the balance passing through A. It will be noted that I have provided gutters 40, arranged along the lower side edges of the hood, for the purpose of catching any moisture which may descend along the ventilators and hood.

80 While I have described more or less precisely the details of construction of my invention, I do not wish to be understood as limiting myself thereto as I contemplate 85 changes in form and proportion of parts and the substitution of equivalents as circumstances may suggest or render expedient without departing from the spirit of my invention.

90 I claim:

1. A smokejack including a plurality of stacks passing through the roof of a roundhouse, and an elongated hood arranged to extend some distance over a track and with 95 said stacks communicating with the interior of said hood, said hood having an unobstructed interior whereby any smoke entering said hood may be withdrawn through said stacks, and means depending from the 100 roof and engaging said hood for supporting said jack in position in the roundhouse.

2. A smokejack including a hood elongated whereby to adapt it to extend longitudinally over a roundhouse stall track and having an open interior throughout its length, a plurality of stack outlets on the upper side of said hood, and vent pipes connected with said outlets.

3. A smokejack including a plurality of 110 stacks passing through the roof of a roundhouse, and an elongated hood arranged to extend some distance over a track and with said stacks communicating with the interior of said hood, said hood having an unobstructed interior whereby any smoke entering said hood may be withdrawn through said stacks, and means on the interior of the round house for supporting said jack in 115 position in the roundhouse.

4. A smokejack comprising an elongated hood positioned beneath and secured to the roof of a roundhouse and arranged to extend over a track, and a plurality of stacks communicating with the interior of said hood and extending through the roof at spaced intervals from each other.

125 Signed at Chicago, Illinois, this 10th day of July, 1922.

ARTHUR J. FILKINS.
